UNITED STATES PATENT OFFICE.

HARRY J. HICK, OF ALLIANCE, OHIO, ASSIGNOR TO THE MCCASKEY REGISTER COMPANY, OF ALLIANCE, OHIO, A CORPORATION OF OHIO.

FILING APPLIANCE.

1,086,769.

Specification of Letters Patent. Patented Feb. 10, 1914.

Application filed June 7, 1909. Serial No. 500,593. Renewed August 26, 1910. Serial No. 579,157.

To all whom it may concern:

Be it known that I, HARRY J. HICK, a citizen of the United States, residing at Alliance, in the county of Stark and State 5 of Ohio, have invented certain new and useful Improvements in Filing Appliances, of which the following is a specification, reference being had therein to the accompanying drawings.

10 This invention relates to a filing appliance adapted to receive and hold in classified arrangement slips of paper or record slips.

For the purpose of illustration, I have, in the accompanying drawings, shown and 15 herein described one form of filing appliance embodying my invention.

Referring to the drawings: Figure 1 is a perspective view of a casing or desk embodying my invention, one of the drawers 20 or slides of the desk being open. Fig. 2 is a side elevation of a portion of the desk showing the slip or bill holding leaves in front elevation. Fig. 3 is a view similar to Fig. 2 with the slip or bill holding leaves 25 removed. Fig. 4 is a view similar to Fig. 2 showing some of the leaves in vertical position. Fig. 5 is a section on line 5—5, Fig. 4. Fig. 6 is a fragmentary plan view of the movable member and the bill holding 30 leaves mounted thereon. Fig. 7 is a fragmentary view of the appliance illustrating details of construction.

In the drawings, 1 indicates a casing or support, which preferably comprises a desk 35 having a drawer or slide 3. The desk may be of any general or preferred construction.

2 indicates as a whole a series of slip or bill holding leaves preferably supported in or upon the desk 1 in convenient position 40 to be operated by the person using or sitting at the said desk. Preferably, the leaves 2 are shown as applied to or mounted in the drawer or slide 3 which is to one side of the desk, particularly when it is of the flat top 45 type, as such application permits the filing appliance to be inclosed and locked up within the desk, or the drawer 3 opened and the appliance operated without affecting or obstructing the use of the desk top. The 50 leaves 2 of the filing device are each of the same size and are preferably arranged to rest horizontally in the drawer 3 when in normal position. Each of the leaves 2 is provided on one or both faces with suitable clips or 55 record-carrying devices 4, each of which

may represent a classified heading or account.

4^a indicate index devices one carried by each clip 4.

4^b indicates an index sheet or key which 60 may be carried by the front face of the first or front end leaf of the series, which leaf is designated 2^a in the drawings.

4^c indicates a base or plate interposed between the series of leaves and the adjacent 65 portion of the casing, which in the illustrated form of the invention comprises the bottom 3^a of the drawer 3. The outer edge of the base 4^c is preferably bent over on itself, as shown at 4^d to form a recess within 70 which the free edge of the lowermost leaf (designated 2^b) engages. This construction forms a convenient means of detachably connecting the leaves 2 to the base 4^c, whereby 75 they may be readily removed from and replaced within the drawer or slide 3. To operate the leaves for the purpose of inserting or removing a record slip to and from a clip 4, they are swung from a horizontal to a vertical position, as shown in Figs. 4 and 5, 80 the drawer side 3^b operating as an abutment or back for the first or front end leaf 2^a and away from which those leaves remaining in normal position move as the said end leaf and succeeding leaves are operated. 85

5 indicate devices which permit the leaves to swing from the horizontal to the vertical position and operate to move those leaves remaining in the normal position outwardly. These devices preferably comprise hinging or pivotal connections 5^a, 5^b, carried, respectively, by the inner or lower edges of each two adjoining leaves, and a pivot pin 5^c between the said connections 5^a, 5^b. The connections 5^a, 5^b, carried by each leaf 2 are arranged to one side of a longitudinal line passing through the center of the leaf. By this construction it will be understood that when one or more leaves 2 are operated to the vertical position the connection of the last operated leaf with the next adjacent leaf will be in front of the longitudinal central line of that leaf and thus maintain it in vertical position. 95

6, 6, indicate vertical guides carried by or 100 formed on the abutment 3^b.

7, 7, indicate slides, one for each of the guides, carried by the leaf 2^a of the series of leaves 2 and arranged to coöperate each with one of the guides 6, it being understood 110

that in the type of leaves 2 and connectors 5 herein described, a leaf or leaves 2 of the series which is or are in vertical position move downwardly or in a direction at substantially right angles to the direction of movement of those leaves in normal position, as the succeeding leaves are swung upwardly one by one.

8 indicate guiding devices preferably comprising grooves 8^a formed in the bottom 3^a of the drawer 3 and slide strips 8^b carried by the base 4^c, adapted to permit the easy sliding movement of the leaves, which remain in horizontal position, outwardly when one or more of the leaves 2 are operated. In addition to their function as guides for the leaves 2, the grooves 8^a and strips 8^b maintain the base 4^c in proper position in the drawer 3 and thus keep the slides 7, 7, aligned with the guides 6, 6, and also prevent any movement of the leaves in a direction at an angle to their normal sliding movements, or longitudinally of the drawer 3 when the latter is opened and closed. Anti-friction devices 25 may be provided between the grooves 8^a and strips 8^b, if desired.

9 indicates a yieldable connection between the leaves 2 and the support and operates to normally return and hold the leaves in normal position, that is, with the pivotal edges of the leaves closely adjacent to or in engagement with the abutment 3^b and with the leaves in superposed relation. The yieldable connection 9 preferably comprises a coiled spring connected at one end, as at 9^a, to the drawer 3, and at its opposite end to the underface of the base 4^c. As the spring 9 is put under tension by the operation of each leaf from a horizontal or prone position to a vertical or upright position, it will be seen that it will operate to move the leaves 2 back into their normal superposed relation within the drawer, when any of the elevated leaves are swung back to horizontal position. 45 The slides 7 preferably comprise flat bearing members arranged to one side of the pivots about which the uppermost leaf swings and engage with the adjacent guides 6 in either position of the said leaf. By this construction it will be seen that when the uppermost leaf is swung from one position to another, the slides 7 operate as levers, their lower or free edges serving as fulcrums, and force the leaves outward slightly against the tension 55 of the spring 9; furthermore, since the spring 9 is placed under tension when the uppermost leaf is operated, it will be understood that the spring, exerting its force through the several leaves, presses the slides 60 7 against the rear wall or back and thus tends to maintain the uppermost leaf in either a horizontal or upright position. The desk 1 may be provided with additional drawers carrying filing leaves 2 similarly 65 constructed and mounted therein, as the

drawer 3 and leaves 2 described herein, if desired. In fact, many alterations in construction and widely differing embodiments and applications of my invention will suggest themselves to those who become skilled or are now skilled in the art of making filing appliances of the class described, without departing from the spirit and scope thereof, as my disclosures and description herein are purely illustrative.

I have endeavored to devise a construction of filing device, embodying a plurality of swingable leaves provided with suitable slip or paper holding devices on either one or both faces, and adaptable for use in a flat top desk of ordinary construction. In many instances of usage the flat top desk has an advantage over any other style of desk. Furthermore, it may be produced more cheaply than the roll top desk of the same drawer capacity. I have sought to combine with a desk of the flat top type a leaf type of filing appliance, in such a manner that the standard construction of such desk need not be changed. The manner in which this has been accomplished by me is a simple, inexpensive and efficient one, and I believe myself to have been the first to have invented the combination or combinations of elements essentially characteristic to the producing of a readily operable device of the class herein described.

What I claim is—

1. The combination with a drawer or slide, of a filing appliance mounted thereon and comprising a series of leaves, means connecting the leaves together and permitting them to be swung on the drawer from a normally horizontal to a vertical position and vice versa, and means for supporting the leaves in vertical position on the drawer or slide.

2. The combination with a drawer or slide, of a filing appliance mounted thereon and comprising a series of leaves, means connecting the leaves together and permitting them to be swung on the drawer from a normally horizontal to a vertical position, and vice versa, and means for supporting the leaves in vertical position on the drawer or slide and guiding their vertical movements.

3. The combination with a drawer or slide, of a filing appliance mounted in said drawer and comprising a series of pivotally mounted leaves arranged to swing from a horizontal to a vertical position and vice versa, and means for yieldably connecting the leaves to the drawer.

4. The combination with a drawer or slide, of a filing appliance mounted on said drawer and comprising a series of pivotally mounted leaves arranged to swing from a horizontal to a vertical position and vice versa, means for yieldably connecting the

- leaves to the drawer, and guiding devices for the leaves.
5. The combination with a drawer or slide, of a filing appliance mounted in said drawer and comprising a series of pivotally mounted leaves arranged to swing from a horizontal to a vertical position and vice versa, means for yieldably connecting the leaves to the drawer, and means for guiding the leaves when one or more of them are operated and operating to prevent longitudinal movement of the filing appliance relatively to the drawer.
6. The combination of a drawer or slide, a filing appliance comprising a series of leaves, means for connecting the leaves together operating when one or more of the leaves are swung into vertical position to move the remaining leaves outwardly, and means for yieldably connecting the leaves to the drawer and operating to return the leaves to normal position when one or more of the leaves are swung back into horizontal position.
7. The combination of a drawer or slide, a filing appliance comprising a series of leaves, means for connecting the leaves together operating when one or more of the leaves are swung into vertical position to move the remaining leaves outwardly, means for yieldably connecting the leaves to the drawer and operating to return the leaves to normal position when one or more of the leaves are swung back into horizontal position, and coöperating guiding devices between the leaves and the drawer.
8. The combination of a slide or drawer, a series of horizontally arranged, superposed leaves mounted in the drawer, means for swingably mounting the leaves relatively to each other, and a yieldable connecting means between the leaves and the drawer, arranged to be put under tension when one or more of the leaves are operated.
9. The combination of a slide or drawer, a series of horizontally arranged, superposed leaves mounted in the drawer, means for swingably mounting the leaves relatively to each other, a yieldable connecting means between the leaves and the drawer, arranged to be put under tension when one or more of the leaves are operated, and guide devices between the lowermost leaf of the series and the bottom of the slide.
10. The combination of a slide or drawer, formed with a side piece, of a series of horizontally arranged superposed leaves mounted in the drawer, means for swingably mounting the leaves relatively to each other, a yieldable connecting means between the leaves and the drawer, arranged to be put under tension when one or more of the leaves are operated, guide devices between the lowermost leaf of the series and the bottom of the slide, a guide carried by the side piece of the said slide, and a slide member carried by the uppermost leaf of the series coöperating with the said guide.
11. The combination of a casing or support, a plate or base slidingly mounted on the casing or support, a series of leaves carried by the plate or base and having pivotal connections between them permitting them to swing from one position to another, and means for yieldingly connecting the plate or base to the said casing or support.
12. The combination of a casing or support, a plate or base slidingly mounted on the casing or support, a series of leaves carried by the plate or base and having pivotal connections between them permitting them to swing from one position to another, means for yieldingly connecting the plate or base to the said casing or support, and guide devices between the base and the casing or support.
13. In a filing appliance, the combination of a series of leaves having pivotal connections between them, and supporting means for the leaves permitting both end leaves of the series to move in directions substantially at fixed angles to each other as any of the leaves between them are swung about their respective pivotal connections.
14. In a filing appliance, the combination of a series of leaves having pivotal connections between them, and supporting means for the leaves permitting both end leaves of the series to move in directions substantially at right angles to each other as any of the leaves between them are swung about their respective pivotal connections.
15. In a filing appliance, the combination of a series of leaves having pivotal connections between them, supporting means for the leaves permitting both end leaves of the series to move in directions substantially at fixed angles to each other as any of the leaves between them are swung about their respective pivotal connections, and means tending to return the leaves to initial position.
16. In a filing appliance, the combination of a series of leaves having pivotal connections between them, supporting means for the leaves permitting both end leaves of the series to move in directions substantially at fixed angles to each other as any of the leaves between them are swung about their respective pivotal connections, means tending to return the leaves to initial position, and means coöperating with the leaf return means tending to maintain the end leaf that is operated in either its operated or initial position.
17. In a filing appliance, the combination of a series of leaves having pivotal connections between them, supporting means for the leaves permitting both end leaves of the series to move in directions substantially at

fixed angles to each other as any of the leaves between them are swung about their respective pivotal connections, means tending to return the leaves to initial position, and means carried by the end leaf that is operated tending to maintain said leaf in either its operated or initial position.

18. In a filing appliance, the combination of a series of leaves having pivotal connections between them, supporting means for the leaves permitting both end leaves of the series to move in directions substantially at fixed angles to each other as any of the leaves between them are swung about their respective pivotal connections, and guide devices for said end leaves.

19. In a filing appliance, the combination of a series of leaves pivotally connected together whereby they may swing from one position to another and vice versa, means for supporting the leaves comprising a support and an abutment, one end leaf being movable relative to said support and the opposite end leaf being movable relative to the said abutment in a direction substantially at a fixed angle to the direction of movement of the other end leaf, as any of the leaves between them are swung about their respective connecting pivots.

20. In a filing appliance, the combination of a series of leaves having pivotal connections between them, supporting means for the leaves permitting both end leaves of the series to move in directions substantially at fixed angles to each other as any of the leaves between them are swung about their respective pivotal connections, and guide devices for said end leaves one of said guide devices operating to prevent shifting of the leaves relative to said supporting means.

21. In a filing appliance, the combination of a support, a series of leaves slidably mounted on the support, pivotal connecting devices between the leaves permitting them to be operated about their respective pivotal connecting devices from a normal position to a position at an angle thereto, and an abutment arranged at an angle to the said support and arranged to slidably support the first leaf of the series that is operated in a plane substantially parallel thereto, all of the operated leaves moving in directions at substantially fixed angles to those leaves not operated during the movement of each operated leaf about its respective pivot.

22. In a filing appliance, the combination of a support, a series of leaves slidably mounted on the support, pivotal connecting devices between the leaves permitting them to be operated about their respective pivotal connecting devices from a normal position to a position at an angle thereto, an abutment arranged at an angle to the said support and arranged to slidably support the first leaf of the series that is operated in a

plane substantially parallel thereto, all of the operated leaves moving in directions at substantially fixed angles to those leaves not operated during the movement of each operated leaf about its respective pivot, and means tending to return the leaves to normal position.

23. A series of frames jointed together and having gearing connections whereby the frames are adapted to be rotated and collocated in rectangular packs at an angle to each other, with a concomitant movement of one pack to and from the plane of the other pack.

24. A series of frames jointed together and having gearing connections whereby the frames are adapted to be rotated and collocated in rectangular packs at an angle to each other, with a concomitant movement of each pack to and from the plane of the other pack.

25. A series of frames jointed together and having gearing connections whereby the frames are adapted to be rotated and collocated either uprightly or prone in rectangular packs, with a concomitant movement of one pack to and from the plane of the other pack.

26. A series of frames jointed together and having gearing connections whereby the frames are adapted to be rotated and collocated either uprightly or prone in rectangular packs, with a concomitant movement of each pack to and from the plane of the other pack.

27. A series of frames jointed together at one end, and having gearing connections whereby the frames may be rotated on their jointed ends to open their free ends apart, and to be collocated in rectangular packs at an angle to each other, with a concomitant movement of one pack to and from the plane of the other pack.

28. A series of frames jointed together at one end, and having gearing connections whereby the frames are adapted to be rotated on their jointed ends to open their free ends apart, and to be collocated in rectangular packs at an angle to each other, with a concomitant movement of each pack to and from the plane of the other pack.

29. An appliance including a series of rotatable frames which may be located uprightly in a rectangular pack, and gearing connections joining the frames whereby a rotation of the frames to a prone position collocates them in a rectangular pack, and vice versa, with a concomitant movement of the rotated frames to and from the plane of the upright frames.

30. An appliance including a series of rotatable frames which may be located uprightly in a rectangular pack, and gearing connections joining the frames whereby a rotation of the frames to a prone position

collocates them in a rectangular pack, and vice versa, with a concomitant movement of each pack to and from the plane of the other pack.

6 31. An appliance including a series of rotatable frames normally located in a rectangular pack, and gearing connections joining the frames whereby a rotation of the frames collocates them in a rectangular pack at an 10 angle to the normal pack, and vice versa, with a concomitant movement of one frame to and from the plane of the other.

15 32. An appliance including a series of rotatable frames normally located in a rectangular pack, and gearing connections joining the frames whereby a rotation of the frames collocates them in a rectangular pack at an angle to the normal pack, and vice versa, with a concomitant movement of each frame 20 to and from the plane of the other.

25 33. An appliance comprising a series of frames, pivotal connections between adjoining frames of the series, and supporting means for the frames permitting both end frames of the series to move in respective paths, which paths are at an angle to one another, as any of the frames between the

end frames are swung about their respective connecting pivots.

34. A filing appliance comprising perpendicular guideways, horizontal track-ways, a plurality of hinged leaves provided with members to engage said guideways and members to engage the said tracks.

35. In a filing appliance, a body, leaves 35 hinged together and adapted to be severally turned to horizontal and vertical positions, the front leaf having a supporting member adapted to travel on the body, and a back leaf hinged to the adjacent leaf and having 40 a vertical bearing on the body.

36. A filing appliance consisting of a plurality of bill-holding leaves hinged together, means to engage one outside leaf and guide it in a perpendicular movement, and means 45 to engage the other outside leaf and permit it to move backward when one or more leaves are drawn down.

In testimony whereof I affix my signature, in the presence of two witnesses.
